CLAIM

The ornamental design for an add-on paint can handle, as shown and described.

DESCRIPTION

FIG. 1 is a front, top and side perspective view of the add-on paint can handle showing my new design;

FIG. 2 is a front elevational view thereof, the rear being a mirror image of the front shown in FIG. 2;

FIG. 3 is a left side elevational view thereof;

FIG. 4 is a right side elevational view thereof;

FIG. 5 is a top plan view thereof; and,

FIG. 6 is a bottom plan view thereof.

FIG.1

FIG. 2

FIG. 3
